SLICING KNIFE

Harry M. Gustafson, Chicago, Ill., assignor to
Simmons Slicing Knife Company, Chicago, Ill.,
a corporation of Illinois

Application November 16, 1945, Serial No. 629,116

5 Claims. (Cl. 30—283)

1

The present invention relates to a slicing knife and more particularly to a slicing knife having an adjustably positioned knife blade relative to a guide.

In slicing operations in the home it is frequently desired to perform slicing operations which will result in uniformity of slices. For example in the slicing of cold cuts of meat and the like it may be desirable to make a number of relatively thin slices of uniform thickness. On the other hand other food stuffs are preferably sliced with a greater thickness as is the case with breads and rolls. One of the problems heretofore encountered in slicing knives has been the difficulty of sharpening such knives, particularly where the knife is provided with either a scalloped or a serrated edge. It, therefore, would be advantageous if it were possible to obtain knife blades which are replaceable much in the manner in which safety razor blades are replaceable. In accordance with the present invention these and other objectives are obtained by providing a slicing knife which has a body portion which serves as a guide. A removable adjustable and replaceable knife blade is mounted parallel to the body of the knife. The knife blade may be positioned in one of a number of different positions so as to provide different spacings for different thicknesses of slices.

It therefore is an object of the present invention to provide an improved slicing knife having a knife blade which is readily adjusted relative to a slicing guide.

A still further object of the present invention is to provide an improved slicing knife having a readily replaceable blade.

Other and further objects of the present invention subsequently will become apparent by reference to the following description taken in connection with the accompanying drawing wherein

Figure 1 is a side view of a slicing knife embodying the present invention;

Figure 2 is a top view of the slicing knife shown in Figure 1;

Figure 3 is a side view of the replaceable knife blade;

Figure 4 is a cross sectional view through the knife supporting stud as seen in the direction of the arrows along the line 4—4 of Figure 1;

Figure 5 is a cross sectional view of a portion of the knife supporting arrangement as seen in cross section in the direction of the arrows along the line 5—5 of Figure 4;

2

Figure 6 is a perspective view of one element of the supporting stud illustrated in Figure 4;

Figure 7 is a perspective view of another element of the supporting stud shown in Figure 4.

A slicing knife constructed in accordance with the present invention is shown in Figure 1 having a body portion 10 and an integrally formed handle 12. The body portion adjacent each of its ends is provided with suitable apertures 14 and 16 for receiving mounting studs 18 and 20 respectively. Between the apertures 14 and 16 the body 10 may have a tapered or narrow configuration formed by the surface 22 so as to provide additional clearance between the body and the adjustably positioned knife blade. A removable knife blade 24 is carried by the studs 18 and 20 parallel to the body 10. The knife blade 24 may have a scalloped edge 26 as shown in Figure 3 or any other suitable form of edge such as a straight knife edge or a serrated knife edge. While a scalloped knife edge has been shown, it will be appreciated that the slicing knife may be provided with a plurality of different knife blades which may be inserted for different slicing operations. It will be noted that at the right end in Figure 3 the knife blade 24 has a relatively narrow notch 28 for engagement with the stud 20 whereas at the left end a much wider notch 30 is provided for engagement with the stud 18. While the two studs may be of similar construction, it is preferable in many cases to provide a difference so that the blade 24 is capable of being placed upon the supports 20 in only one direction. This is particularly desirable for knife blades of the serrated edge type where the points of the teeth of the edge are inclined in one direction.

The stud 18 is shown in detail in Figure 4 and is mounted in a recess 32. The stud 18 has immediately beneath the head an enlarged portion 34 which may be knurled as shown or otherwise given a configuration so that the stud 18 is fixedly mounted in the recess 32 against rotation. The stud 18 has a reduced diameter portion 36 which adjacent one end is threaded at 38 to receive a thumb nut 39. A sleeve 40 is mounted directly upon the reduced diameter portion 36. The sleeve 40 carries a plurality of spacing washers 42. The sleeve 40 which is also shown in perspective in Figure 6 is provided with an enlarged portion 44 which preferably is knurled so as to be readily grasped by the fingers. The sleeve portion 40 has an aperture 46 arranged so that the sleeve 40 serves as an eccentric member. The

eccentric member is provided so that when the blade 24 is placed upon the studs 18 and 20 the portion 44 may be grasped with the fingers and rotated to apply a certain amount of longitudinal tension to the blade 24. Thereafter the thumb nut 38 is engaged to tighten the washers 42 against the blade 24. It will be noted that the sleeve 40 is somewhat shorter than the total distance between the outer surfaces of the outer washers so that the thumb nut 38 applies a coercive force against the washer to frictionally engage and retain in position the knife blade 24.

If desired the right end stud 20 may be of similar construction to the stud 18, but as previously mentioned it is preferable, particularly for serrated replaceable knife blades to form the stud 20 so that it has a smaller diameter shaft which fits into the notch 28. The smaller diameter shaft is provided with a plurality of washers 48 which are retained in positioned by a thumb screw 50. An additional washer 52 is provided adjacent the body 18 of the knife blade. The washer 52 may have a different thickness than the washers 48 that is of a thickness equal to the thickness of the collar 44 on the eccentric sleeve 40 on the other stud 18. If desired the blade 24 may be positioned adjacent the larger washer 52 of the stud 20 and adjacent the sleeve 44 on the stud 18 in order to make slices of a minimum thickness. For maximum thickness the knife blade 24 is placed adjacent the thumb nuts 38 and 50. The knife blade 24 may be placed at any desired intermediate position as shown in Figure 2 between the washers 48 and 42.

From the foregoing it will be appreciated that the present invention contemplates a slicing knife with an adjustably positioned blade to which tension is applied to give proper rigidity and minimum flexibility to the blade 24 during use. It furthermore will be appreciated that a new replaceable blade may be inserted at any time that the old blade has outlived its usefulness.

While for the purpose of illustrating and describing the present invention, a preferred embodiment has been shown in the drawing, it is to be understood that the invention is not to be limited thereby since such variations in the structural elements and in their arrangements are contemplated as may be commensurate with the spirit and scope of the invention set forth in the following claims.

This invention is hereby claimed as follows:

1. A slicing knife comprising an elongated body member, a handle for said body member, a pair of supporting studs carried by said body member at longitudinally spaced points thereon, a sleeve mounted on one of said studs, a plurality of spacing washers, certain of said washers being slidably mounted on said sleeve and others of said washers being slidably mounted on the other stud, a removable knife blade mounted on said studs in spaced relation to said body member and disposed between selected pairs of said spacing washers, said sleeve having an enlarged grip-

ping portion and an eccentric knife-tensioning portion, said knife blade having a recess therein to receive said eccentric portion, and thumb nuts respectively threaded on said studs for squeezing together all said parts mounted on each of said studs thereby to secure said blade under tension.

2. A slicing knife as set forth in claim 1, wherein in the washers which are mounted on said sleeve are disposed on said eccentric portion intermediate said gripping portion and one of said thumb nuts.

3. A slicing knife as set forth in claim 1, wherein in the length of said eccentric portion is less than the combined thickness of the knife blade and the washers mounted on such portion.

4. A slicing knife comprising an elongated body member, a handle for said body member, a pair of supporting studs carried by said body member at longitudinally spaced points thereon, an eccentric sleeve mounted on one of said studs, a plurality of spacing washers, certain of said washers being slidably mounted on said sleeve and others of said washers being slidably mounted on the other stud, a removable knife blade mounted on said studs parallel to said body member and disposed between selected pairs of said spacing washers, said knife blade having an inclined notch therein to receive said sleeve, a finger grip on said sleeve for turning said sleeve to place said blade under tension, and thumb nuts respectively threaded on said studs for squeezing together all said parts mounted on each of said studs thereby to secure said blade under tension.

5. A slicing knife comprising an elongated body member, a handle for said body member, a pair of supporting studs carried by said body member at longitudinally spaced points thereon with one of said studs provided with cam means extending longitudinally thereof, a plurality of spacing members carried by each of said studs, a removable knife blade mounted on said studs parallel to said body member and disposed between selected pairs of said spacing members, said knife blade being recessed to provide an edge against which said cam means is adapted to be urged to tension the blade, means for shifting said cam means into tensioning contact with the said edge, and means respectively engaging the ends of each of said studs for squeezing together all the parts associated therewith thereby to secure the blade under tension.
